UNITED STATES PATENT OFFICE.

ADAM L. SMITH, OF YOUNGSTOWN, OHIO.

HOT-AIR FURNACE.

Application filed February 11, 1921, Serial No. 444,167. Renewed February 14, 1922. Serial No. 536,537.

To all whom it may concern:

Be it known that I, ADAM L. SMITH, a citizen of the United States, residing at Youngstown, in the county of Mahoning and State of Ohio, have invented certain new and useful Improvements in a Hot-Air Furnace, of which the following is a specification.

This invention relates to improvements in hot air furnaces, and has particular reference to hot air furnaces, utilizing gas as a heating medium.

The principal objects of the invention are; to provide an improved furnace structure wherein cold air is caused to pass through a series of heated tubes forming a part of heating chambers without becoming saturated with gases and other products of combustion; to provide a furnace structure wherein a maximum heating efficiency is obtained, and to provide an improved burner wherein both air and gas are utilized as fuel.

For the purpose of illustrating this invention there is shown in the accompanying drawing one form thereof which is at present preferred, since the same has been found in practice to give satisfactory and reliable results, although it is to be understood that the various instrumentalities of which the invention consists can be variously arranged and organized and that the invention is not limited to the precise arrangement and organization of these instrumentalities as herein shown and described.

35 In the drawing:

Figure 1 is a sectional side elevation of the invention.

Figure 2 is top plan view of the same, partly broken away to show the disposition 40 of the air circulating tubes.

Like characters of reference indicate like or similar parts throughout the several views, in which:

A designates the outer casing of a furnace 45 which rests upon a suitable heat resisting foundation B and has communicating with the lower portion thereof a cold air intake conduit 1, while formed in the top wall 2 of the furnace are hot air outlet openings 3 about which are formed annular flanges 4 for receiving hot air pipes (not shown).

Arranged within the furnace casing A, and enveloped thereby, but spaced some distance from the walls thereof is a heating 55 chamber C, through the lower portion of which extends an air intake conduit 5 which

communicates with the casing 6 of a heating element generally designated by D. Carried within the intake conduit 5 is a fuel supply pipe 7 which has a vertically extending branch 60 coupled to its end upon which is carried a pin point burner 8. Both the branch and pin point burner 8 extend a short distance upwardly in the casing 6, and arranged thereover in the casing is a baffle screen 9 for thoroughly mixing the incoming air with the fuel from the burner 8. Tapped into the top 10 of the casing 6 are burner tubes 11 which have a screen 12 arranged therein so that upon lighting the combustible mixture of gas and air very hot flames of the proper intensity and size will result.

Extending from a water reservoir or tank (not shown) through the cold air intake 1 of the furnace into the heating chamber C is 75 a water supply pipe 13 which communicates through a vertical pipe section 14 with the coils 15 of a water heater E arranged in the heating chamber C above the heating element D. The upper coil of the water heater E is 80 extended to form a return pipe 16 to the reservoir and it is pointed out that in addition to providing hot water when the furnace is operated, the coils 15 form baffles for distributing the heated air arising from 85 the burner, which otherwise would be of greatest intensity at the top of the chamber.

Arranged about the heating chamber C adjacent the top 17 thereof is a supplementary air heating chamber 18 through which extend a plurality of air pipes 19 to permit the passage of cold air therethrough, and communicating with the chamber 18 through the conduits 20 is a primary air heating chamber F which is arranged above the 95 chamber C and extends to a point adjacent but spaced from the side walls of the furnace as illustrated in Figure 1. The primary air heating chamber F also has a plurality of air pipes designated by 21 arranged therein 90 so that the cold air coming in through the inlet 1 will not only circulate around the heating chamber C but through and about the air heating chambers 18 and F consequently ensuring maximum efficiency of the 100 heating system. The primary heating chamber F is directly connected through the pipes 22 with the chamber C so that the heated air passing from the chamber C thereto will also pass downwardly to the chamber 18 and 110 from thence out through the stack 23 connected, as illustrated with the chamber 18.

In order to insure proper distribution of incoming air a foraminated plate 24 is arranged between the wall of the chamber C and the wall of the furnace casing A above the inlet 1 so that the incoming air will circulate around and through the chambers as above described.

If desirable the casing A may be protected by some heat resisting covering such as 10 asbestos or fire brick (not shown), and attention is particularly called to the fact that none of the obnoxious products of combustion such as gases and the like come into contact with the heated air, thereby eliminating the most undesirable feature of hot air heating systems.

Attention is also called to the fact that expansion and contraction of the tubes, pipes and heating elements is also permitted 20 as no rigid connections are effected between the same and the furnace casing, consequently cracking or breaking of the same through the action of heat and cold will be positively prevented.

25 In operation the burners of the heating element D are lighted and immediately the cold water in the coils 15 of the hot water heater E will be heated and a circulation will take place. The flames arising from 30 the heating element strike the coils of the hot water heater, and the heated air issuing therefrom also strikes the same, both will be distributed to uniformly heat the heating chamber C. The heated air in the chamber 35 C will pass through the conduits 22 to the primary heating element E and from thence will pass downwardly to the secondary heating element 18 and outwardly through the stack 23. The cold air coming in through 40 the inlet 1 will pass upwardly through the pipes 19 in the secondary heating element and through the pipes 21 of the primary heating element and outwardly through the outlet openings 3, in the meantime however

a complete circulation of the incoming cold 45 air will take place around the outside of the heating chambers in the manner above described in detail thus effecting a maximum efficiency of the heating system. Attention is called to the fact that none of the products of combustion come into contact with the heated air.

From the foregoing description taken in connection with the accompanying drawing it is thought that a clear and comprehensive 55 understanding of the construction, operation, and advantages of the invention may be had, but while I have shown and described the device as embodying a specific structure, I desire it to be understood that 60 such changes may be made in said structure, as do not depart from the spirit and scope of the invention as claimed.

What I claim is:

In a furnace of the class described, a supporting base, a closed casing mounted on said base, a cold air supply conduit opening into the lower portion of said casing through one side wall thereof and hot air outlets in the top of said casing, a main 70 heating chamber within the casing with the walls thereof spaced from the casing walls, heating means in said chamber, an auxiliary air heating chamber arranged above said main heating chamber and extending adjacent to and spaced from said casing walls, pipes connecting said main and auxiliary heating chambers, a supplementary air heating chamber surrounding said main chamber at a point below the auxiliary chamber 80 and having a plurality of cold air pipes extending therethrough, pipes connecting said auxiliary and supplemental heating chambers, and an exhaust pipe leading from the bottom of said supplemental chamber. 85

In testimony whereof, I affix my signature hereto.

ADAM L. SMITH.
